WILLIAM W. CHEWNING, OF CHESTER, PENNSYLVANIA

WORK HANDLING DEVICE

Application filed January 12, 1931, Serial No. 508,360. Renewed March 22, 1932.

My invention relates to a work handling device.

In accordance with my invention, I provide a work handling device which is adapted for use in connection with flanged work, such as I-beams, H-beams, railway rails, girders, columns, stringers, floor beams, and double beam lintels.

The device embodies a pair of companion grip-members, which are supported by cables, in such a manner that the cables automatically draw the grip-members together, for secure clamping engagement with the work, preventing slippage. The grip-members may be conveniently applied to the flanged work, without first raising the work. The work handling device is of simple construction, strong and durable.

In the accompanying drawings, forming a part of the specification, and in which like numerals are employed to designate like parts throughout the same,

Figure 1 is a side elevation of the work handling device embodying my invention,

Figure 2 is a plan view of the same, the cables being shown in section,

Figure 3 is a horizontal section taken on line 3—3 of Figure 1,

Figure 4 is an inner face view of one of the grip-members,

Figure 5 is an outer face view of the same,

Figure 6 is an outer face view of the companion grip-member,

Figure 7 is an inner face view of the same,

Figure 8 is a longitudinal section taken on line 8—8 of Figure 2,

Figure 9 is a plan view of a modified form of work handling device.

In the drawings, wherein for the purpose of illustration is shown a preferred embodiment of my invention, the numerals 10 and 11 designate companion grip-members. Each grip-member is, preferably, a casting or forging. Each grip-member comprises a pair of vertical sides 12, spaced, as shown. The sides 12, in each pair, are rigidly connected near their lower ends by a horizontal transverse web 13, integral therewith, and a vertical web 14 is formed integral with the horizontal web 13, and is spaced from the sides 12. At its upper

end, the vertical web 14 is rigidly connected with the upper ends of the sides 12, by means of horizontally arranged grooved sheaves 15, integral with the web 14, and the sides 12. The sheaves 15, of the grip-member 10, are spaced a greater distance apart than the sheaves 15 of the grip-member 11, so that these sets of sheaves are not in longitudinal alignment. The arrangement of sides, webs and sheaves afford transverse passages 14', through which cables to be described, extend. The vertical web 14, of the grip-member 10 is formed wider than the vertical web 14 of the grip-member 11. The grip-members 10 and 11 are provided in their lower portion with horizontal slots 16, and these slots pass through the sides 12 and horizontal webs 13, as shown. The grip-members 10 and 11 are also provided with handles 17, in the form of rods, which extend through openings 18 formed in the sides 12, and these handles are spaced from the horizontal and vertical webs 13 and 14.

The numerals 19 and 20 designate cables, which are bent upon themselves, between their ends. The cable 19 passes outwardly of and in engagement with the sheaves 15 of the grip-member 10, and the intermediate portion of this continuous cable is arranged within a horizontal groove 21, formed in the lower portion of the vertical web 14, of the grip-member 10. The free ends of the cable 19 extend upwardly and these free ends are attached to a ring 22, or the like. In a similar manner, the cable 20 passes outwardly of and in engagement with the sheaves 15, of the grip-member 11, and the intermediate portion of this cable engages within a horizontal groove 23, formed in the lower portion of the vertical web 14. The upper ends of the continuous cable 20 are attached to the ring 22. The ring 22 is, of course, connected with a cable, or the like, leading to suitable hoisting mechanism for raising and lowering the device.

In Figure 8, I have shown a slightly modified form of the invention. In this figure, the sheaves 15', corresponding to the sheaves 15, are rotatable instead of being fixed, and are separate from the sides 10 and vertical webs 14. The sheaves 15' are rotatable upon shafts 100.

16', passing through openings in the upper ends of the sides 12 and vertical webs 14. The shafts are held against displacement by cotter pins 17', or the like. The other parts remain identical with those shown and described in connection with the first form of the invention.

In the use of the device, the same is lowered in proximity to the work, and sufficient slack is provided in the cables 19 and 20 to permit an operator, or operators, grasping the handles 17, to spread the grip-members 10 and 11, so that they may be arranged upon opposite sides of the flange 24, of the work, so that the slots 16 may receive the flange. It is obvious that it will be unnecessary to first raise the work in applying the grip-members to the same, as is ordinarily necessary when passing a cable or chain about the work. As soon as the device is raised, the downward pull of the load, through the co-action of the cables and sheaves, causes the grip-members to be moved horizontally inwardly, with respect to the work, thereby having clamping or binding action therewith. It has been found that the work will not slip when being suspended by the grip-members 10 and 11.

It is also seen that the grip-members may be applied to various kinds of work having an available flange upon which the device may be mounted, as explained. This is important in unloading different work.

The operation of the second form of the device is similar to that of the first, and it is thought to be unnecessary to describe the same. In the first form of the device, the cables slide upon the various stationary sheaves, while in the second form of the invention, the sheaves are rotatable.

While the device is particularly well adapted to be used in handling flanged work, or work having a projecting flange, yet it is not necessarily restricted to this use, as different types of engaging jaws may be provided.

It is to be understood that the forms of my invention herein shown and described are to be taken as preferred examples of the same, and that various changes in the shape, size and arrangement of parts may be resorted to without departing from the spirit of my invention, or the scope of the subjoined claims.

Having thus described my invention, what I claim is:

1. A work handling device, comprising a pair of grip-members, each grip-member having a recess formed in its inner face for receiving the flange of the work, and cables for supporting the grip-members, each cable having a relatively movable engagement with the outer side of the corresponding grip-member, and extending inwardly beyond the same, and connected with the companion grip-member, the arrangement being such that the cables draw the upper and lower ends of the

grip-members together, and also serve to suspend the same.

2. A work handling device, comprising a pair of opposed grip-members, each grip-member having a slot formed in its inner face for receiving the flange of the work, and a flexible element engaging the outer portion of each grip-member and extending inwardly across the same and engaging the outer portion of the companion grip-member, the arrangement being such that the flexible elements suspend the grip-members and also urge them inwardly toward each other. 70

75 3. A work handling device, comprising a pair of opposed grip-members having slots in their inner faces for receiving the flange of the work, and a flexible element engaging the outer side of the upper portion of each grip-member and extending inwardly across the same and engaging the companion grip-member at a point beneath the upper portion of the same, the arrangement being such that the flexible elements suspend the grip-members and also urge them inwardly toward each other. 80

85 4. A work handling device, comprising a pair of opposed grip-members provided with inner work-engaging means, a sheave carried by the upper portion of each grip-member, and a flexible element passed about the outer side of the sheave of each grip-member and extending inwardly across such grip member and engaging the companion grip-member at a point beneath its sheave. 90

95 5. A work handling device, comprising a pair of opposed grip-members provided with inner work-engaging means, each grip-member embodying a generally vertical web and a pair of sheaves arranged near the upper end of said grip-member, and a flexible element folded upon itself for use in connection with each grip-member, the folded flexible element affording a pair of strands engaging the outer sides of the sheaves of the corresponding grip-member and extending inwardly across the same with its intermediate portion passed about the outer side of the generally vertical web of the companion grip-member, and means connecting the free ends of the strands of the flexible elements. 100

105 6. A work handling device, comprising a pair of opposed grip-members provided with inner work engaging means, each grip-member embodying a generally vertical web having a grooved part and a pair of sheaves arranged near the upper end of the grip-member, and a looped flexible element for each grip-member embodying sides and an intermediate portion, the sides of the flexible element engaging the outer sides of the sheaves of the corresponding grip-member and extending inwardly across the same and having its intermediate portion engaging the grooved part of the generally vertical web of the companion grip-member. 110

115

120

125

130

7. A work handling device, comprising a pair of opposed grip-members, each grip-member including a pair of spaced sides, a horizontal web rigidly connecting the sides and having a horizontal groove formed upon its inner face, a generally vertical web disposed between the sides and spaced therefrom and rigidly connected with the horizontal web, stationary sheaves arranged between the sides and generally vertical web and rigidly connected therewith, the arrangement of the sides, webs, and sheaves affording transverse passages in the grip-member, a cable for each grip-member bent upon itself for affording sides and an intermediate portion, the sides of each cable engaging the outer sides of the sheaves of the corresponding grip-member and extending inwardly through the passages of such corresponding grip-member and having its intermediate portion extending around the generally vertical web of the companion grip-member, and means for connecting the free ends of the cables.

25 8. A work handling device, comprising a pair of opposed grip-members, each grip-member including a pair of spaced sides, a generally horizontal web rigidly connecting the lower portions of the sides and having a generally horizontal groove upon its inner face, a generally vertical web disposed between the sides and spaced therefrom and rigidly connected with the horizontal web, a shaft connecting the upper ends of the sides and generally vertical web, rotatable sheaves arranged between the sides and generally vertical web and carried by the shaft, the arrangement being such that transverse passages are provided beneath the sheaves, and a cable for use in connection with each grip-member, said cable being folded between its ends for providing an intermediate portion and sides, the sides of each cable engaging the outer sides of the sheaves of the corresponding grip-member, and extending inwardly through the passages and having its intermediate portion passed about the outer side of the generally vertical web of the companion grip-member, and means for connecting the free ends of the cables.

50 9. A work handling device, comprising opposed grip-members, each grip-member being provided upon its inner face with a flange receiving groove, a handle arranged upon the outer side of each grip-member and attached thereto, and a flexible element engaging the outer side of the upper portion of each grip-member and extending inwardly across such grip-member and engaging the companion grip-member, the arrangement being such that the flexible elements serve to suspend the grip-members and urge them inwardly toward each other.

In testimony whereof I affix my signature.

65 WILLIAM W. CHEWNING.
